DESIGN FOR A FOOD DISPENSER

Georges Binon, New York, N. Y., assignor to The Food Dispenser Company, a corporation of Connecticut

Application October 19, 1938, Serial No. 80,560

Term of patent 14 years

To all whom it may concern:

Be it known that I, Georges Binon, a subject of the King of Belgium, residing at New York, in the county of New York and State of New York, have invented a certain new, original, and ornamental Design for a Food Dispenser, of which the following is a specification, reference being had to the accompanying drawing, forming part thereof.

In the drawing,

I claim:

The ornamental design for a food dispenser, substantially as shown.

GEORGES BINON.
